(74) Attorney, Agent, or Firm—Banner & Witcoff, Ltd.

(57) **CLAIM**

The ornamental design for a set of key button arrangement for a handset, as shown and described.

DESCRIPTION

FIG. 1 is a front view of a key button arrangement for a handset showing our new design; and,

FIG. 2 is a perspective front view thereof.

The broken line showing of the remainder of the handset is for illustrative purposes only and forms no part of the claimed design.
